[57] CLAIM

The ornamental design for an electronic timer, as
shown and described.

DESCRIPTION

FIG. 1 is an isometric view of an electronic timer showing
my new design;

FIG. 2 is a top plan view thereof;

FIG. 3 is a front elevational view thereof;

FIG. 4 is a right side elevational view thereof, the left
side being a mirror image thereto;

FIG. 5 is a rear elevational view thereof;

FIG. 6 is a bottom plan view thereof.
